MELTING AND CASTING OF METALS

Eric Crisp Lewis, Putney, London, England, assignor to Magnesium Elektron Limited, London, England, a British company

Application August 14, 1940, Serial No. 352,597
In Great Britain August 16, 1939

4 Claims. (Cl. 22—69)

This invention relates to the melting and casting of metals, and has for an object to provide an improved apparatus of the kind comprising a crucible adapted to contain molten metal and gas under pressure and having a delivery pipe adapted to extend below the level of the molten metal, its upper end being outside the crucible for delivery of molten metal and means to increase the gas pressure to force the metal up the delivery pipe and out of its upper end. An example of such an apparatus is described and illustrated in the specification of Patent No. 514,994.

According to the invention, the upper end of the delivery pipe communicates with a delivery channel member leading outwardly from the crucible and having means to enclose the channel in all directions except in the direction of the outlet end of the channel, and a sufficient part of the means for enclosing the channel is readily removable to permit a straight cleaning rod or pyrometer tube to be inserted in the upper end of the delivery pipe and down to the molten metal. The pipe may require replacement before the channel member and the channel member may therefore be made of more permanent construction than the pipe and the pipe may be readily detachable from the channel member so that the latter can be readily removed and a new pipe fitted in its place. For this purpose, the channel member may contain a hole comprising a continuation of the bore of the delivery pipe, the latter being secured by bolts to the underside of the channel member.

The above and other features of the invention (which features are defined in the appended claims) will now be described by way of example with reference to the accompanying drawing, wherein:

Figure 1 is a side elevational view of a delivery pipe with channel member made in accordance with the invention;

Figures 2 and 3 are a front elevation and a plan view respectively of the parts shown in Figure 1.

The delivery pipe 6 is tapered with its smaller end uppermost and is made of thin sheet steel, for example 16 gauge and provided with stiffening ribs 7, 8, of similar thin material. The reason for using such thin material is that the tube will rapidly be heated by the molten metal to a temperature above the solidification point of the metal, thus minimizing risk of freezing of the metal in the tube. Near the lower end of the tube is a hole 9 through which the gas in the crucible can escape when the level of the molten metal

falls below the level of this hole and this avoids spouting of metal out of the upper end of the tube which tends to occur when the molten metal in the crucible has fallen to a low level. The upper end of the delivery pipe has a plate 12 welded to it and this plate is bolted by bolts 11 against the end surface of a base plate 13 of the channel member with its bore in line with an opening 14 in the said member. The opening 14 is tapered in the same direction as the delivery pipe and is of slightly smaller diameter so that any metal which may become frozen in the opening 14 can be readily pushed downwardly and will fall down the delivery pipe into the molten metal. The channel member comprises a V-channel section 15 welded to the base plate 13 and extending from a position slightly rearwardly of the opening 14 to a convenient forward position for delivery of metal into a ladle or mould. The channel extends from the crucible at an angle between the horizontal and vertical and with its outer end lower than its inner end so that the molten metal is held against the channel by gravity so that it gravitates smoothly along the channel. The rear end of this V-channel is closed by a rear wall 16 which extends upwardly for some distance above the opening 14. Two upstanding walls 18, 19, are welded at their lower ends to the inside surface of the V-section 15 and are parallel to each other and to the V-section. A flat lid 20 is hinged to the rear wall 16 at 21 and normally lies upon the upper edges of the walls 18, 19. The V-section 15, walls 18, 19 and lid 20 form a channel which is enclosed in all directions except in the downward or delivery direction so that any spouting molten metal will be diverted down the channel and tendency to oxidation of metal at the upper end of the delivery pipe and in the channel is minimised. The lid 20 can, however, be lifted to provide free access to the opening 14 and delivery pipe so that a cleaning rod or brush or a pyrometer tube can be inserted into the opening 14 and pushed in a straight line down the delivery pipe into the molten metal.

The channel member can be maintained in use for an almost indefinite period, whereas the delivery tube becomes corroded and requires to be replaced after much less use. The delivery pipe can be readily removed from the channel structure by removing the bolts 11 and can be easily replaced by a new delivery pipe.

Sulphur dust may be dropped into the openings 22, 23, between the walls 18, 19, and adjacent parts of the channel section and sulphur vapours

or sulphur dioxide produced therefrom will penetrate into the interior of the channel through small openings 24, 25, left between the spot welds by which the walls 18, 19, are welded to the V-section 15. Alternatively, an opening 26 may be provided to which a tube may be connected for conducting an inert atmosphere such as sulphur dioxide or air containing sulphur dust into the channel to minimise oxidation of the molten metal. When the expulsion of the molten metal from the delivery tube is stopped and the level of the molten metal falls into the delivery tube, the inert atmosphere will be drawn into the delivery pipe and minimise oxidation of metal therein. If sulphur is dusting on to the metal in the ladle in which the metal is caught as it leaves the channel, the sulphur laden air or sulphur dioxide therefrom will likewise be drawn up the channel and may render other supply of sulphur or sulphur dioxide unnecessary.

It will be observed that the whole unit comprising the channel member and the delivery pipe is carried by the plate 13 which can be bolted in position on the crucible in the place indicated by the numeral 10 in Figure 1 of the specification of Patent No. 514,994 with the delivery pipe inclined in about the same way as shown in that figure and bolted in position in a readily removable and gas-tight manner.

The channel is shown fixed at right angles to the axis of the delivery pipe and whilst this is a convenient arrangement, the channel may be fixed at any other suitable angle.

Instead of hinging the cover 20 in position, it may be fixed detachably by a loose pin or other suitable means.

Different sizes of delivery pipes may be desirable for different types of work and the exchange of one unit for another is readily effected.

I claim:

1. Apparatus for dealing with molten metals comprising a crucible adapted to contain molten metal and gas under pressure, a delivery pipe for the molten metal adapted to extend from the upper part of the crucible downwardly and below the level of the molten metal and having its lower end freely suspended in the metal and otherwise constructed so as to be readily removable from the crucible, its upper end being outside the crucible for delivery of molten metal, means to increase the gas pressure in the crucible to force the metal up the delivery pipe and out of its upper end, a delivery channel member communicating with the delivery pipe and leading outwardly from the crucible at an angle between the horizontal and vertical and with its outer end lower than its inner end so that the molten metal is held against the channel by gravity so that it gravitates smoothly along the channel, and means to enclose the channel in all directions except in the direction of the outlet end of the channel, a sufficient part of the means for enclosing the channel being readily movable to permit a straight cleaning rod or pyrometer tube to be inserted in the upper end of the delivery pipe and down to the molten metal.

2. Apparatus for dealing with molten metals comprising a crucible adapted to contain molten metal and gas under pressure, a delivery pipe for the molten metal adapted to extend from the upper part of the crucible downwardly and below the level of the molten metal and having its lower end freely suspended in the metal and otherwise constructed so as to be readily removable from

the crucible, its upper end being outside the crucible for delivery of molten metal, means to increase the gas pressure in the crucible to force the metal up the delivery pipe and out of its upper end, a delivery channel member communicating with the delivery pipe and leading outwardly from the crucible at an angle between the horizontal and vertical and with its outer end lower than its inner end so that the molten metal is held against the channel by gravity so that it gravitates smoothly along the channel member to which the delivery pipe being secured to the channel in a readily detachable manner in line with a hole in the channel which hole forms a continuation of the bore in the pipe and leads to the channel, and means to enclose the channel in all directions except in the direction of the outlet end of the channel, a sufficient part of the means for enclosing the channel being readily removable to permit a straight cleaning rod or pyrometer tube to be inserted in the upper end of the delivery pipe and down to the molten metal.

3. Apparatus for dealing with molten metals comprising a crucible adapted to contain molten metal and gas under pressure, a delivery pipe for the molten metal adapted to extend from the upper part of the crucible downwardly and below the level of the molten metal and having its lower end freely suspended in the metal and otherwise constructed so as to be readily removable from the crucible, the pipe being made of thin sheet iron of the order of $\frac{1}{8}$ of an inch thickness and having thin stiffening fins so as to absorb but little heat from the molten metal, in reaching the temperature of the molten metal thereby minimising risk of freezing of the metal in the pipe, its upper end being outside the crucible for delivery of molten metal, means to increase the gas pressure in the crucible to force the metal up the delivery pipe and out of its upper end, a delivery channel member communicating with the delivery pipe and leading outwardly from the crucible at an angle between the horizontal and vertical and with its outer end lower than its inner end so that the molten metal is held against the channel by gravity so that it gravitates smoothly along the channel and means to enclose the channel in all directions except in the direction of the outlet end of the channel, a sufficient part of the means for enclosing the channel being readily movable to permit a straight cleaning rod or pyrometer tube to be inserted in the upper end of the delivery pipe and down to the molten metal.

4. Apparatus for dealing with molten metals comprising a crucible adapted to contain molten metal and gas under pressure, a delivery pipe for the molten metal adapted to extend from the upper part of the crucible downwardly and below the level of the molten metal and having its lower end freely suspended in the metal and otherwise constructed so as to be readily removable from the crucible, a base plate adapted to be detachably secured to the crucible, to the underside of which base plate the delivery pipe is detachably secured, its upper end being outside the crucible for delivery of molten metal, means to increase the gas pressure in the crucible to force the metal up the delivery pipe and out of its upper end, a delivery channel member communicating with the delivery pipe and leading outwardly from the crucible at an angle between the horizontal and vertical and with its outer end

lower than its inner end so that the molten metal is held against the channel by gravity so that it gravitates smoothly along the channel, and means to enclose the channel in all directions except in the direction of the outlet end of the channel, a sufficient part of the means for en-

5

closing the channel being readily movable to permit a straight cleaning rod or pyrometer tube to be inserted in the upper end of the delivery pipe and down to the molten metal.

ERIC CRISP LEWIS.
